AXIAL FLOW COMPRESSOR PLANT

Adolf Baumann, Wettingen, Switzerland, assignor to Aktiengesellschaft Brown Boveri & Cie, Baden, Switzerland, a joint-stock company

Application January 31, 1939, Serial No. 253,838
In Germany February 1, 1938

2 Claims. (Cl. 230—115)

This invention relates to axial flow compressors and to mechanisms for regulating the compressor output and preventing surging.

The characteristic curves for an axial flow compressor are basically different from the corresponding curves for radial flow compressors and the methods of regulation that are applicable for radial flow compressors are not satisfactory in the case of axial flow compressors.

Objects of this invention are to provide axial flow compressors with new mechanisms for regulating the same, the apparatus and methods being characterized by high efficiency and stability of operation at low compressor outputs. An object is to provide compressor plants including an axial flow compressor, an engine or motor for driving the compressor at a substantially constant speed for which the compressor output will satisfy the maximum volume and/or pressure demands, an air or gas turbine, and a manually or automatically controlled valve for diverting to the turbine such fraction of the total amount of air or gas pumped by the compressor as will result in the desired regulation condition at the point of use of the compressed air or gas, i. e. constant pressure, constant volume, predetermined pressure-volume characteristic, etc.; the power developed by the turbine being employed to supplement the engine or motor. An object is to provide axial flow compressors that have mechanisms operable to maintain a desired condition of constant pressure, constant volume or predetermined pressure-volume relationship at the point of use of the compressed air or gas when a constant speed motor drives the compressor at a speed such that the maximum volume demand is delivered at the required pressure, the regulating mechanism being operable to divert through an expansion turbine such fraction of the compressor output which will maintain the desired condition.

These and other objects and advantages of the invention will be apparent when taken with the accompanying drawing in which:

Fig. 1 is a curve sheet showing the pressure-volume and load-volume characteristics for axial flow and radial flow compressors;

Figs. 2 to 5, inclusive, are similar characteristic curves for axial flow compressors regulated in accordance with this invention; and

Fig. 6 is a diagrammatic illustration of an axial flow compressor plant embodying this invention.

In Fig. 1, the heavy solid line curves L_a , P_a , show the variation of the load L and discharge pressure P of an axial flow compressor with changes in the output or volume V of gas or air

delivered by the compressor, and the heavy dotted line curves, L_r , P_r , show the corresponding variations in the case of a radial flow compressor. The designs of the two compressors are assumed to be such that the power inputs to the compressors are equal when they deliver the same normal volume V_n of air or gas at the same pressure. This condition is indicated by the crossing of the pressure curves P_a , P_r and the load curves L_a , L_r at points 1, 1', respectively.

It will be seen that the power input or load L_r of the radial compressor increases and the pressure P_r decreases with increasing volume output V , but the load L_a and pressure P_a for the axial flow compressor drop rapidly with an increase in the output. The so-called "surging limit" at a decreased output V_a of the axial flow compressor is much closer to the normal output V_n than is the surging limit volume V_r for the radial flow compressor. The significance of these characteristics is that, upon a decrease in output volume, the axial flow compressor reaches an unstable condition more rapidly than does a radial flow compressor, and that the load or power consumption rises rapidly to point 2'a as the pressure rises to point 2'a. The operating points 2'r, 2r for a radial flow compressor at the surging limit V_r are indicated on curves L_r , P_r , respectively.

One method of obtaining stability in the operation of radial flow compressors has been to pump the limiting quantity V_r through the compressor for all lesser consumption demands and to blow off that quantity of gas or air which was in excess of some small demand volume, for example the volume V_3 . The load and pressure for the radial flow compressor are thus stabilized at the values of points 2'r and 2r, respectively. Similar regulation in the case of an axial flow compressor would require the high power input at level L_2 for all low output volumes, and would deliver the compressed gas or air at the high pressure level P_2 .

This increasing pressure at reduced output is usually unnecessary and may be undesirable. In accordance with this invention, the normal volume V_n is pumped through the compressor at the pressure level P_3 —1, and the fraction in excess of the required volume V_3 is blown off, thus holding the power input at the value $L'a$ when the compressed gas or air is discharged at atmospheric pressure. This blow off at the normal discharge pressure insures stable operation but the power input $L'a$ is substantially above the corresponding power input L_r for the radial flow compressor at reduced outputs. Increased

efficiency is obtained by discharging the surplus gas or air through an expansion turbine coupled to the compressor, the net power input to the axial flow compressor unit then dropping along curve $L''a$ as the volume demand decreases. Line $L''a$ drops below curve L and thus indicates that axial flow compressor and expansion turbine system is more efficient than the radial flow compressor at low outputs. The discharge pressure is kept constant over a range of output demand and it is not necessary to provide additional regulating members or to alter the rotary speed of the compressor to prevent surging.

This type of regulation is particularly useful when the consumption requirements are such that the pressure decreases as the volume decreases, Fig. 2. Assuming that the demand varies between a volume V_1 at pressure P_1 and a smaller volume V_3 at lower pressure P_3 , the axial compressor is driven at such speed that the point 1, corresponding to P_1 , V_1 , falls on the pressure-volume curve. According to the invention, the compressor is operated at the lower pressure level, point 2 on the pressure-volume curve P_a , corresponding to the larger compressor output V_2 . The blowing off of air or gas to increase the output from V_1 to V_2 effects a substantial decrease in the load as the power input drops from point 1' on the load curve L_a to point 2'. The quantity ΔV in excess of the demand requirement may be expanded in a turbine to supply power for driving the compressor, and the net power input is thereby reduced still further to point 3' on the curve $L''a$.

This method of regulation and stabilization of compressor operation can be employed to maintain any desired operating condition at the point of use of the compressed air or gas, for example a condition of constant pressure, constant volume or predetermined parabolic pressure-volume relationship. In all cases the expansion turbine serves as a regulating member for establishing the desired condition and for preventing surging.

As shown by the curves of Fig. 3, the regulated condition may be that of a constant volume, for example V_3 , that may normally be supplied at a pressure P_2 corresponding to operating point 2 on the curve P_a . The output of the compressor at operating point 2 exceeds the demand requirement V_3 by a surplus ΔV that may be discharged through the recovery turbine. The power consumption when operating at point 2 on curve P_a is substantially less than that for operation at point 1 at which the required volume V_3 constitutes the total compressor output at a pressure P_1 . The power consumption at operating point 1 is indicated by point 1' of curve L_a , and the power drops to point 2' on curve L_a if the surplus volume ΔV is exhausted to atmosphere or to point 3' of curve $L''a$ if the surplus is discharged through the turbine. Any desired volume, for example volume V_4 , may be set in the usual way by adjusting the regulating member by hand. The surplus $\Delta'V$ may be employed in the turbine to reduce the power input to point 4', and surging is prevented at all reduced demand volumes as the same volume V_2 is discharged by the compressor regardless of the lesser volume that is to be supplied to the point of use.

Similarly, as shown by the curves of Fig. 4, the regulated condition may be that of constant pressure P_1 or P_3 corresponding to operating points 1 or 3, respectively, on the pressure-volume curve P_a . The volume of air or gas passing through the compressor at any selected setting of the

delivery pressure is the maximum volume that can be discharged at that pressure and the surplus ΔV or $\Delta'V$ above the actual demand at pressure P_1 or P_3 , respectively, is blown off to the expansion turbine through a pressure-regulating valve, and the net power input drops with decreasing consumption along the net load lines L' and L^3 , respectively, as the consumed volume varies between points 1 and 2 on pressure line P_1 and points 3 and 4 on pressure line P_3 .

Another type of regulated condition is that of simultaneous variation of pressure with changing volume demand in accordance with a selected parabolic pressure-volume curve such as indicated by lines A or B of Fig. 5. The particular parabolic curve of operating conditions is set by hand adjustment and the axial flow compressor is driven at that speed for which the pressure-volume curve P_a crosses the control condition line A at operating point 1 corresponding to maximum compressor output at the maximum demand pressure. As the volume demand decreases, a greater or less surplus volume ΔV is blown off to obtain the corresponding reduction in outlet pressure, and the operating point drops to point 2 on curve P_a when the delivery pressure falls to point 3 on curve A. The corresponding drop in the load is from point 1' to point 2' on the load curve L_a when the surplus volume ΔV is discharged to open air, or from point 1' to point 3' on curve L if the expansion turbine is used. A greater surplus volume $\Delta'V$ may be available when the control member is set for operation on curve B corresponding to a smaller volume consumption.

The method of the invention is exceedingly simple and it has approximately the efficiency of the speed regulating methods without requiring auxiliary surging gears to insure stable operation; the compressor at all times delivering the full volume along the pressure-volume characteristic and any surplus being delivered to the expansion turbine to reduce the power consumption.

A typical assembly of a compressor and regulating equipment, as shown diagrammatically in Fig. 6, includes the axial flow compressor C and expansion turbine T on the same shaft S with a motor or engine M. The compressor has a suction line 11 and pressure line 12 for supplying compressed air or gas to a conduit 13 that leads to the point of use and to the intake line 14 of the turbine T. The intake line 14 has a regulating member or valve 15 for controlling that fraction of the total compressor output that is to be delivered to the turbine to maintain the desired control condition in delivery conduit 13. The turbine exhaust line 16 may include a valve 17 to control the discharge of the exhaust to open air or, alternatively, to return the exhaust gas or air through line 18 to the suction line 11 of the compressor.

It will be apparent that control valves and mechanisms for regulating the venting of the surplus compressor output to atmosphere or to the turbine may be of various known manual and automatic types, and that the choice of the apparatus will depend to some extent on the particular type of control that is desired in any given case.

I claim:

1. A compressor assembly comprising an axial flow compressor having a pressure line and a continuously open unobstructed suction line, power means driving said compressor at a substantially constant speed at which the compressor output to the pressure pipe at the required demand pres-

sure is not less than the maximum volume demand, a delivery conduit into which said pressure line opens, and regulating means to prevent surging and to maintain a desired operating condition at said delivery line when the load demand drops below its maximum value; said regulating means comprising a conduit branching from said pressure line, and a regulating valve in said branch conduit for diverting from the delivery conduit that portion of the compressor output which at the constant operating speed exceeds the volume corresponding to the desired operating condition at the delivery line, said regulating

means including also power recovery means for decreasing the load imposed on said power means in accordance with the portion of the total compressor output that passes to said branch conduit, said power recovery means comprising an expansion turbine having as its intake line the said branch conduit.

5 2. A compressor assembly as defined in claim 1 in which the power recovery means comprises an exhaust line opening into said compressor suction line.
